UNITED STATES PATENT OFFICE.

JOSEPH B. ULLMAN, OF WASHINGTON, DISTRICT OF COLUMBIA.

FINGER RING.

Application filed February 19, 1927. Serial No. 189,573.

This invention relates to a finger ring, and it consists in the novel features hereinafter described and claimed.

An object of the invention is to provide a ring adapted to be worn upon the finger and which may be removed therefrom and used as a game piece in the form of a top or teetotum.

With this and other objects, the structure includes an annular band adapted to circumscribe the finger of the wearer and which is provided at one side with a pintle and at its opposite side with a portion having prongs adapted to receive and hold a jewel. The head portion is provided with a transversely disposed recess and a pivot pin is located in the said recess, the axis of the pivot pin being in alignment with the axis of the pintle. One or more disks are disposed within the recess and are loosely mounted upon the pivot pin for free turning thereon. When more than one disk is employed, they are spaced from each other by suitable spacing washers also loosely mounted upon the pivot pin. The disk, or disks are provided at their peripheral edges with facets upon which valuation characters are marked or placed and these characters may be similar to the spots on dice faces or representations of the faces of playing cards.

In the accompanying drawings:

Figure 1 is a side elevational view of the ring.

Figure 2 is a transverse sectional view thereof cut on the line 2--2 of Figure 1.

Figure 3 is a perspective view of the disks used in the ring.

Figure 4 is a transverse sectional view of the ring showing a modified arrangement of the number of disks used.

The ring includes an annular band 1, preferably of precious metal, and adapted to be worn upon the finger. The band is provided at one side with a head portion 2 having prongs 3 adapted to retain a jewel 4 thereon. For all practical purposes the prongs and the jewel may be dispensed with.

The head portion 2 is provided with a transversely disposed recess 5 which opens at its ends at the side edges of the band 1, as best illustrated in Figures 2 and 4 of the drawing. A pivot pin 6 extends across the intermediate portion of the recess 5 and is secured at its ends in constituting the band portion and the head portion of the ring.

The axis of the pivot pin 6 is disposed in

the median plane of the band 1. Disks 7 are loosely mounted upon the pivot pin 6 and are received within the recess 5. The disks are spaced from the side walls of the recess 60 and from each other by spacing washers 8 which are also loosely mounted upon the pivot pin 6.

The peripheral portions of the disks 7 are substantially flush with the end edges of the recess 5, as best illustrated in Figures 2 and 4. The end edges of the disks 7 are provided with plane facets 9, upon which are placed value characters 10 as furnished with dots or inserted jewels or the representations 70 of the faces of playing cards. The axis pivot pin 6 is in alignment with the axis of a pintle 11 which is provided upon the exterior surface of the band 1, and which is disposed diametrically opposite the head portion 2 75 of the ring.

When used as a game or toy device, the ring is removed from the finger of the wearer and grasped between the fingers and the thumb and positioned so that the pintle 11 80 rests upon a relatively level surface. By twisting the fingers, in a usual manner, the ring is spun upon the said surface and the band 1 rotates about the axes of the pintle 11 and the pivot pin 6. The disk, or disks 7 85 will have a tendency to remain at a state of rest, and consequently, this inertia will cause the axes of the ring and the pivot pin 6 to rotate with relation to the disks so that the facets of the disks are exposed successively, at the ends of the recess 5 and at the opposite side of the head portion 2 of the ring. When the ring stops spinning, it will fall upon one side or the other and consequently, the value characters upon the exposed facets 90 of the disks will be displayed to view upon the said plane surface. Thus, the ring may be used as a game or a toy device and each player is entitled to the credit for the value of the characters which each player brings 100 up at his turn of the device in play.

From the foregoing description taken in conjunction with the accompanying drawing, it will be seen that a combined ring and play device of simple and durable construction is provided, and that the same is of an ornamental character and may be easily carried upon the finger of a man, and is readily accessible for use as a device of amusement.

From the foregoing description of the construction of my device, the operation

thereof will be readily understood and it will be seen that I have provided a simple, inexpensive and efficient means for carrying out the objects of the invention.

5 While I have particularly described the elements best adapted to perform the functions set forth, it is obvious that various changes in form, proportion and in the minor details of construction may be resorted to 10 without departing from the spirit or sacrificing any of the principles of the invention.

Having described the invention, what is claimed is:

15 1. A ring comprising a band provided at one side with a head portion having a transversely disposed recess and at its opposite side with a pintle, a pivot pin disposed transversely across said recess and having its axis in alignment with the pintle, a disk 20 loosely mounted upon the pivot pin and housed within the recess and having peripheral facets adapted to be exposed at the ends of the recess, and means for distinguishing the value of the respective facets.

25 2. A ring comprising a band provided with a head portion having a recess extending transversely therethrough, and provided opposite said head with a pintle, a pivot pin disposed transversely across said recess and having its axis in alignment with the axis of the pintle, disks housed in the recess and 30 loosely mounted upon the pivot pin, spacing washers located between the disks and loosely mounted upon the pivot pin, said disks having peripheral facets distinguished from each other by valuation characters.

35 3. A ring comprising a band provided with a head portion having a recess passing therethrough, and provided with a pintle, said head portion having means for receiving a jewel, a pivot pin passing transversely 40 across the recess and having its axis in alignment with the pintle, and a disk located in the recess and loosely mounted upon the pivot pin and having facet surfaces distinguished from each other by valuation characters.

45 4. A ring comprising a band provided at

its side with a head portion, and having at its opposite side a pintle, the head portion having a recess passing transversely therethrough opening at the sides of the band, a disk loosely mounted upon the pivot pin and housed in the recess and having its peripheral edge substantially flush with the end edges of the recess, the peripheral edge of the disk being divided into plane facets and the facets having distinguishing valuation characters.

50 5. In a finger ring, a band, means thereon to assist in the spinning thereof, and additional means on said band providing chance playing elements upon the spinning of said ring and forming ornaments therefor when the ring is not in play.

55 6. In a finger ring, a band, a pintle carried on the periphery to permit spinning thereof, and means carried on said band diametrically opposed to said pintle providing chance playing elements upon the spinning of said ring and forming ornaments therefor when the ring is not in play.

7. In a finger ring, a band, a pintle carried on the periphery to assist in the spinning thereof, and rotatable elements carried on the band opposed to said pintle, said elements being brought into play as chance devices upon the spinning of said ring and forming ornaments therefor when the ring is not in play.

75 8. A ring comprising a band, a pintle on the periphery to permit spinning thereof, and movable playing elements housed within said band and adapted for use upon the spinning of said ring.

80 9. A ring comprising a band having a head thereon provided with a transverse recess, a pintle on the periphery of said band opposed to said head to assist in the spinning of said band and movable members housed within said recess and operable as chance playing elements upon the spinning of said band.

In testimony whereof I affix my signature.

JOSEPH B. ULLMAN.
